(57) **CLAIM**

The ornamental design for a beverage dispense valve, as shown and described.

DESCRIPTION

FIG. 1 is a left side view of the design, with a handle in a first position; it being noted that a right side view is a mirror image to the left side view of FIG. 1 and that the handle itself does not form part of the design;

FIG. 2 is a left side view of the design, with the handle in a second position;

FIG. 3 is a front view of the design, with the handle in the first position;

FIG. 4 is a rear view of the design, with the handle in the first position;

FIG. 5 is a top view of the design, with the handle in the first position;

FIG. 6 is a bottom view of the design, with the handle in the first position; and,

FIG. 7 is a perspective view of the design, with the handle in the first position.

The broken line showing of the handle is included for the purpose of illustrating the environment and forms no part of the claimed design.
